UNITED STATES PATENT OFFICE.

JOHN ANDREW KOLLMYER, OF KEOKUK, IOWA, ASSIGNOR OF NINETEEN-TWENTIETHS TO GEORGE DEXTER RAND, OF SAME PLACE.

ROTARY CUT-OFF VALVE.

SPECIFICATION forming part of Letters Patent No. 598,153, dated February 1, 1898.

Application filed May 6, 1897. Serial No. 635,854. (No model.)

To all whom it may concern:

Be it known that I, JOHN ANDREW KOLLMYER, residing at Keokuk, in the county of Lee and State of Iowa, have invented certain new and useful Improvements in Rotary Cut-Off Valves for Steam and other Engines, of which the following is a specification, reference being had therein to the accompanying drawings.

10 This invention relates to cut-off valves for steam and similar engines.

The object of the invention is to produce a valve in which the opening and closing by rectilinear movement may be quickly effected and always freedom of exhaust secured, and which may also serve to cut off the steam or other elastic gas with a celerity dependent upon the working of the engine or governor and by a continuous forward movement; and 20 the further object of the invention is to improve the construction and combination of parts of a cut-off valve.

Figure 1 is a broken side elevation of so much of an engine as is needful to show the general relation of parts in my invention. Fig. 2 is a partial elevation and partial section of the crank-shaft and gearing. Fig. 3 is a sectional plan of engine and gear. Figs. 4 and 4^a are elevations of a gear and connections preferred for rotating the valve, showing different positions. Fig. 4^b is a broken detail, a reverse view from Fig. 4. Fig. 5 is a central longitudinal section or diagram of a steam-cylinder and valve-seats according to my invention. Fig. 6 is a side elevation of valve-plugs. Fig. 7 is a broken elevation and section of the valve-plugs in their seats. Figs. 8 and 9 are cross-sections of valve seat and plug in different positions.

40 In many respects these illustrations are merely diagrammatic, as a great number of changes in construction may be made without departing from the spirit of the invention. No cylinder-heads are shown in Fig. 5.

45 The cylinder 1 is of usual construction for steam-cylinders. A supply of live steam at 2 has access to the valve-seats 3 3^x by passing through the valve-plugs 4 4^x, said plugs being hollow, having side or annular openings, and the outer ends of said plugs being closed, as indicated in dotted lines. The two

plugs are connected by a spindle 6, so that both plugs may move together, and exhaust is effected through ports or passageways 7 7^x.

The valve-seats 3 3^x are hollow cylinders 55 with radial slots or passageways therein. Preferably these slots are wider at the outer end, so as to give a quick and free exhaust. The slots a a^x are the same length as corresponding slots b b^x in the hollow cylindrical valve-plugs. The slots a in valve-seat 3 are not in line longitudinally with the slots a^x in seat 3^x, but the slots in one valve-seat are in line with the closed ports of the other and the valve-plugs are of corresponding construction. 60 The valve-plugs are closed hollow cylinders at the outer ends, and these closed rings serve to close the ports a or a^x when the plug is in proper position. The ports a or a^x are alternately opened and closed by 70 the longitudinal movement of the valve-plugs through stem 8, as usual in slide-valves. The longitudinal movement of the plugs is effected by the cam or eccentric or in other usual manner. The longitudinal movement of the two 75 plugs from the position of Fig. 1 toward the left opens all the passageways a^x by reason of all the passageways b^x being in line therewith. At the same time the exhaust 7 is opened by the movement of the ring or cup part of plug 4 80 away from the openings c. In this described position of the valve the steam from chamber 2 passes through openings b^x a^x to the cylinder. Then the cut-off comes into operation, as will be described.

85 The cutting off of the steam is effected by the rotation of the valve-plug in its seat and is quick or slow, according to predetermined conditions or factors. As there are a large number of passageways through the valve-plug, 90 the steam or gas finds ready access to the cylinder. In the device illustrated, with eight passageways in the valve-seat and a similar number in the plug, a turn of the plug of about twenty-two and one-half degrees will close 95 the valve from open position, or vice versa. As a small overlap is allowed, this movement may be a little more than twenty-two and one-half degrees; but it will be readily understood that the movement is slight. The same 100 rotary movement which closes the ports a^x by movement of plug 4^x brings the opening

b in plug 4 in line with the passages *a* in seat 3, so that the next reverse longitudinal movement of the plugs will open all the passages in 4, leaving them to be closed as a cut-off by 5 a further rotation of the plugs in the same direction. A mechanism by which this intermitting rotation of the valve-plugs, always in one direction, may be effected will now be described.

10 In Fig. 3 the general relation of the parts is shown, the cylinder being designated by numeral 1, as in other figures. The piston, piston-rod, and pitman bear the usual relation to the crank-shaft 10, which is supported 15 on frame A. The longitudinal movement of the valve is effected by the usual eccentric 100 and reciprocating rod 99, to which shaft 8 is connected so as to reciprocate, being left free to rotate.

20 The valve-rod 8, which reciprocates in bearings in the frame, may be either splined or polygonal and passed through a short shaft 40, which shaft is supported in bearings B on the frame. The rotation of gear 11, fixed to 25 shaft 40, causes the rod 8 and its plugs to rotate. As a means of causing this gear 11 and rod or shaft 8 to rotate intermittently always in one direction and under control of the governor I have illustrated a mechanism connected to the crank-shaft; but it must be understood that it may be connected to some other rotating shaft.

30 The fly-wheel 12 carries a weight 13 on arm 14, yieldingly connected to sleeve 18 on the 35 shaft near the hub of the fly-wheel. A spring 15, connected by link 16 to the arm or weight, tends to retire the weight toward the center of the fly-wheel, while centrifugal force tends to throw this weight outward. This connection 40 of the weight or governor to the sleeve 18 causes the sleeve, while generally partaking of the rotary motion of the shaft, to be turned at times either a little in advance of its median position on the shaft when the

45 governing-weight is thrown outward by a rapid rotation of the fly-wheel or a little behind this position when the rotation of the shaft permits the spring to draw the weight inward. Sleeve 18 carries a bevel-gear 19, 50 which meshes with gear 20, and thus rotates shaft 21, supported in suitable bearings. This shaft 21 should make on the average a determined number of revolutions—in the present instance, two rotations—for each rotation of the main shaft; but as the sleeve 18 and its gear may be either advanced or retarded by the governor the relative initial point of rotation of the shaft 21 may not agree with that of the driving-shaft. Shaft 21 car-

60 ries a one-tooth disk 30 and a mutilated disk 22, a concave portion being cut from said disk 22. In line with this concave portion at the side of the disk 30 there is a tooth 23. This tooth 23 engages gear-wheel 11, through 65 which the shaft 8 passes, so that each revolution of the shaft 21 gives one impulse to wheel 11 and turns shaft 8 a distance great

enough to cut off the steam by the rotation of the valve-plugs, and as the initial position of shaft 21 is controlled by the governor this cutting off of the steam will be effected more or less quickly after the reciprocation of the valve, according to the position of the governor. When the tooth 23 has passed out of engagement with one of the teeth of gear wheel or pinion 11, the convex side of the mutilated disk 22 comes into one of the concave spaces 24 of a disk 25, which disk 25 is rigidly connected to pinion 11. The engagement of these disks prevents the rotation of the gear 11, and thus of the valve, until the finger or tooth 23 again comes around. By this means a second rotary impulse is given to the valve, and as these impulses occur about twice for each revolution of the main shaft the cut-off of steam will take place at corresponding intervals. Of course the number of teeth in the driving-gear 11 will bear definite relation to the ports in the valve and valve-seat.

90 From the foregoing it may be understood that a valve constructed to operate on the general principles set forth may be moved with extreme rapidity. As the ports are thrown quickly open by longitudinal movement of the valve and closed by rotation proportioned to the speed of the engine or to the adjustment of the governor, there is little tendency to withdraw steam through narrow 95 passages kept open for a relatively long time.

99 Prior to my invention I believe cylindrical valve-seats for somewhat similar purposes have been known, and a cylindrical valve has been caused to oscillate or rock therein to act as a cut-off. This causes the wear on the 100 valve and seat to come on the same points all the time, and such a valve is soon worn or disabled, whereas the valve of the present invention, constantly rotating in one direction, may be maintained in good condition 105 for a very long time.

110 In valves of the general character to which I have referred the cut-off has generally been effected by an eccentric mechanism, which operates with something like a uniform rate 115 of speed, and the valve slowly closes by its oscillation. In the present invention the rotation of the valve is effected by a very quick movement, the valve starting its rotation at full speed and continuing its movement until 120 closure is completed at this high speed, then remaining at rest until the next rotary movement. The initial point of position or instant of time at which this rotary or cut-off movement shall begin and end are determined by 125 the governor.

130 It must be understood that the governor need not be of the particular form shown and described herein. Having set forth the general principles and illustrated one mode of carrying the same into operation, skilled mechanics will be able to apply the same to equivalent constructions.

What I claim is—

1. In a valve-gear as described, the intermittently-rotating valve, the driving-pinion thereof having a notched holding-disk attached, and the driving-shaft having a tooth for engagement at each rotation with a tooth of said pinion, and having a notched disk engaging the notches of the holding-disk on the valve-plug to prevent rotation, all combined substantially as described.

10 2. The connected cylindrical valve-plugs closed at their outer ends and having radial slots in their sides, the hollow cylindrical valve-seats having slots corresponding in number with the slots in the plugs, but enlarged at the ends through which the steam exhausts, means for moving the valve-plugs longitudinally, means for rotating the valve-plugs intermittently in one direction, and a connection from the governor controlling the 15 initial rotary movement, all combined substantially as described.

20 3. The reciprocating valve-rod and its valve-plugs and the valve-seats, the rotating sleeve through which said valve-rod moves, said

sleeve and rod being connected for synchronous rotation, the gears fixed to said rotating sleeve, a single-tooth gear propelled by a shaft under control of the governor and engaging one of the gears on the said rotating sleeve, and a mutilated disk propelled by the same 25 governor-controlled shaft acting on the second gear of the sleeve to prevent undue rotation, all combined substantially as described.

4. A reciprocating and intermittently-rotating valve-plug, the valve-seat therefor, the reciprocating valve-rod and a single continuous rotating valve-operating shaft parallel therewith, and having an intermittent gear engaging the valve-rod to rotate the same at intervals in one direction, and the governor 30 controlling the initial position of the rotating shaft, all combined substantially as described.

In testimony whereof I affix my signature in presence of two witnesses.

JOHN ANDREW KOLLMYER.
